FIG. 1

INVENTOR
HARRY C. CURRIER
BY *Paul Paul*
ATTORNEY

UNITED STATES PATENT OFFICE.

HARRY C. CURRIER, OF MINNEAPOLIS, MINNESOTA.

STATIONERY-FILE.

1,252,092.

Specification of Letters Patent.

Patented Jan. 1, 1918.

Application filed July 15, 1915. Serial No. 40,098.

To all whom it may concern:

Be it known that I, HARRY C. CURRIER, a citizen of the United States, resident of Minneapolis, county of Hennepin, State of Minnesota, have invented certain new and useful Improvements in Stationery-Files, of which the following is a specification.

My invention relates to devices for keeping a supply of note or letter paper, bill heads, envelops, carbon paper and the like convenient for use, and the object of the invention is to provide a file particularly adapted for use in a drawer of a desk where its contents will be readily accessible and where it will be protected from dust and dirt.

A further object is to provide a file in which the pockets are removable to allow substitution of other pockets of varying size and to adapt the device for different lines or sizes of envelops and paper.

The invention consists generally in various constructions and combinations, all as hereinafter described and particularly pointed out in the claims.

In the accompanying drawings forming part of this specification,

Figure 1 is a plan view of a stationery file embodying my invention,
Fig. 2 is a longitudinal sectional view of the same,
Fig. 3 is a perspective view of one of the pockets removed from the file,

Fig. 4 is a sectional view of one corner of a desk, showing the file fitting in the drawer.
In the drawing, 2 represents the outer shell or box of the file, having an open top and a closed bottom. Within this box a series of pockets are arranged. The outer 40 pocket 3 is preferably secured in the box and is divided by a partition 3' into separate compartments adapted to receive envelops placed endwise therein. The pocket is at an incline and the ends of the envelops 45 will project beyond the open end of the pocket where they can be conveniently reached for removal. The next pocket 4 is seated upon the pocket 3 and has its inner end abutting against a stop 5 that is punched up out of the bottom of the box. This box has side walls 6 with inwardly turned upper edges 7 and an upwardly turned rear edge 8 and between the walls 6 a slide 9 is preferably arranged to adapt the 55 pocket for different lengths of envelops that may be placed therein. This pocket is pref-

erably deeper than those for the letter paper, and also has a partition dividing it into separate compartments.

10, 11, 12 and 13 represent a series of 60 pockets placed one upon another and of varying length, the lower pocket 10 resting upon the pocket 4 and seated against a stop corresponding to the stop 5 and having a slide 14 corresponding in its function to the 65 slide 9 in the pocket 4. The other pockets 11, 12 and 13 contact with the rear wall 15 of the box, the upper ends of all these pockets being in alignment with one another. A receptacle 16 is fitted into the recess in the inner end of the box, resting upon the pocket 13, and has a cover 17. This receptacle is adapted to receive stamps and other articles used around a desk or typewriter.

In Fig. 4 a desk 18 is illustrated, of conventional design having a flat top 19 and a drawer 20 in which the box 2 is fitted. When this drawer is closed, the contents of the box will be concealed and protected, and when the drawer is drawn out, all the envelops, note paper, carbon paper and the like will be exposed where it can be conveniently removed for use.

The device may be made in various sizes, 85 the number of pockets and the size thereof may be modified, and in various ways the details of construction herein shown and described may be modified and still be within the scope of my invention.

I claim as my invention:

1. A stationery file comprising a sheet metal box having a floor, side walls, an end wall and open at the opposite end and top, a sheet metal plate having an upright front 95 wall and inclined inwardly and downwardly therefrom fitting within said box at the open end thereof and forming the floor of a pocket adapted to receive envelops and the like, and a series of pockets arranged above 100 said plate and downwardly and inwardly inclined between said first named pocket and said end wall, said pockets being loosely arranged in said box and having their upper ends on substantially the same level.

2. A stationery file comprising a box open at the front end and closed at the rear end and having side and rear walls of substantially the same height and an open top, 110 pockets fitting one above the other within said box and rearwardly and downwardly inclined therein and of varying length, the

upper ends of said pockets being open and those in the rear of the forward pocket being on substantially the same level, the open end of the forward pocket being below the 5 level of the others and accessible through the open end of said box, said pockets being comparatively shallow and adapted to contain articles, such as stationery.

3. A stationery file comprising a box having an open top and stops struck up out of the bottom of said box, pockets fitting within said box and resting upon one another, the lower pockets being seated against said stops and the upper pockets being seated 10 against the inner wall of said box, and all of said pockets being inclined backwardly and downwardly from the front to the rear of said box.

4. A stationery file comprising a sheet metal box having an open top and front end, sheet metal pockets fitting within said box and downwardly inclined from the front to the rear of the box and arranged one above the other therein, the forward pockets being 20 deeper than those in the rear thereof and accessible through said open end, said pockets increasing in length from the ends of the box toward the middle portion thereof and being removable one from the other.

5. A stationery file comprising a sheet metal box having side walls and an end wall of substantially the same height and an open top, a series of sheet metal pockets fitting within said box, one above the other, and rearwardly and downwardly inclined therein, the upper inner pocket being seated against said end wall, there being a triangular space formed between said pocket and the top of said side and end walls and a correspondingly shaped stamp box fitting within 30 said space and having the top thereof flush substantially with the tops of said pockets.

6. A horizontal stationery file comprising a sheet metal box having a floor, side walls, an end wall and open at the opposite end and the top, a pocket having an inclined floor fitting within said box at the open end thereof and secured to the walls of the box 40 and adapted to receive envelops and the like,

and a series of removable pockets fitting within said box and resting one upon another therein and having open outer ends.

7. A stationery file comprising a sheet metal box having side and rear walls of substantially the same height and an open top and end, comparatively shallow sheet metal pockets fitting within said box and extending from side to side thereof and one above the other and rearwardly and downwardly 55 inclined therein, some of the forward pockets being deeper than the others to adapt them for envelops and the like and accessible through the open end of the box, the lower pockets being seated on the horizontal bottom of said box and some of the upper pockets having their inner ends seated against the vertical rear wall of the box, the upper ends of said pockets being open for the insertion of stationery and the like therein. 60

8. A file for stationery comprising a box having an open top and pockets fitting therein, each pocket being composed of sheet metal having an upwardly turned rear edge and upwardly projecting side walls terminating in inwardly projecting flanges, and a comparatively narrow slide fitting between 70 said side walls and guided by the bottom of the pocket and said inwardly projecting flanges.

9. A stationery file comprising a sheet metal box, rectangular substantially in form, for fitting within a desk drawer and extending from side to side therein and having a closed inner end, an open top and front end, a series of sheet metal pockets fitting within 80 said box and downwardly and inwardly inclined thereon, the lower pockets having their inner ends seated on the bottom of said box and the upper pockets having their lower ends seated against the rear end wall of said box, the forward ends of the upper pockets being on substantially the same level and open for the insertion of stationery and the like, and said pockets fitting loosely between the side walls of the box and removable one from the other therein. 90

In witness whereof, I have hereunto set my hand this 9th day of July 1915.

HARRY C. CURRIER.
